DESIGN FOR A DOLL OR SIMILAR ARTICLE

Shirley Mae Chmielensky, Baldwin, N. Y.

Application December 1, 1943, Serial No. 111,859

Term of patent 3½ years

To all whom it may concern:

Be it known that I, Shirley Mae Chmielensky, a citizen of the United States of America, residing in Baldwin, county of Nassau and State of New York, have invented a new, original, and ornamental Design for a Doll or Similar Article, of which the following is a specification, reference being had to the accompanying drawing, forming part thereof.

Fig. 1 is a front view of a doll or similar article showing my new design.

Fig. 2 is a front perspective view thereof with the skirt portion removed.

Fig. 3 is a rear perspective view with the skirt portion removed.

The dominant feature of my design resides in the portions best shown in Figs. 2 and 3 on the drawing.

I claim:

The ornamental design for a doll or similar article, substantially as shown and described.

SHIRLEY MAE CHMIELENSKY.
